UNITED STATES PATENT OFFICE

WILLIAM C. MERWARTH, OF EASTON, PENNSYLVANIA, ASSIGNOR TO PENNSYLVANIA PUMP & COMPRESSOR COMPANY, OF EASTON, PENNSYLVANIA, A CORPORATION OF PENNSYLVANIA

VALVE-LIFTING DEVICE

Application filed October 27, 1926. Serial No. 144,465.

This invention relates to valve lifting devices and particularly to a fluid pressure actuated means for lifting and holding a compressor valve from its seat to unload the 5 compressor.

An object of the invention is to provide an improved form of valve lifter for compressors adapted, when the valve is in its raised or unloading position, to provide a pressure 10 tight enclosure whereby full receiver pressure will be supplied to the unloading device and leakage of fluid will be prevented.

Another object of the invention is to provide a piston loosely movable within an unloading cylinder to which fluid under pressure is adapted to be admitted, the piston in moving being adapted to carry with it a second piston member having fingers extending to and engaging the valve plate.

Another object of the invention is to provide a cylinder for a piston movable to operate compressor unloading devices which has a seat at one end of the cylinder adapted to contact with a surface on the piston when 25 the piston is in its valve unloading position.

Another object of the invention is to provide a pressure tight seat between one end of the cylinder and a second piston member moved by a piston operating within the cylinder so that during normal operation of the 30 compressor fluid will be prevented from leaking from the compressor intake passages out through the unloading devices.

With these and other objects in view my 35 invention consists in the features of construction and operation set forth in the following specification and illustrated in the accompanying drawings.

In the accompanying drawing annexed 40 hereto and forming a part of this specification, I have shown my invention embodied in a compressor unloading device operated by lifting and holding an inlet valve in an inoperative or open position but it will be understood that the invention can be otherwise 45 embodied and that the drawing is not to be construed as defining or limiting the scope of the invention, the claims appended to this specification being relied upon for that purpose.

The figure of the drawing shows a central sectional view of a complete valve and unloading device made according to the present invention.

In the above mentioned drawing, I have 55 shown but one embodiment of the invention which is now deemed preferable, but it is to be understood that changes and modifications may be made within the scope of the appended claims without departing from the 60 spirit of the invention.

Briefly, and in its broadest aspect, my invention comprises the following principal parts: First, a valve movable between open and closed positions during normal operation of the compressor; second, a piston member having fingers adapted to contact with and lift the valve from its seat; third, another piston member movable within a cylinder and adapted to force the piston member 70 carrying the fingers in a direction to lift the valve, these two piston members forming a two-part piston; fourth, a seat formed on said cylinder adapted to be in contact with a surface of one of the pistons when 75 the piston has been moved to a position to lift the valve; fifth, a cover plate for one end of the cylinder secured in pressure tight relation to the cylinder; sixth, closely co-acting surfaces between the supporting member for 80 the valve and the piston member carrying the valve engaging fingers adapted to be in contact when the valve lifting member is in its retracted position; seventh, means to admit fluid under pressure to the space within 85 the cylinder to actuate the piston members and carrying the valve lifting fingers, and resilient means normally forcing the piston members and carrying the fingers toward their retracted position.

Referring more in detail to the figure of the drawing, I provide a valve assembly having a valve seat 10, a cover plate 11 and a valve plate 12 mounted in a suitable opening formed in the cylinder wall 13 of a compressor. The valve shown is of the inlet type adapted to admit fluid being compressed from inlet passages 14 to the space within the cylinder 15. It will be understood that the compressor may be simple or compound and the 95 100

intake passages 14 may admit fluid to the low or a high pressure cylinder.

To support the valve assembly 10-11 and 12 in operative position in the compressor 5 wall 13, a yoke supporting member 16 is provided having a ring portion 17 adapted to contact with the valve seat 10. The lower portion of this yoke member 16 is formed as a cylinder 18 open at the lowermost end and

10 having a cover plate 19 at this end to close it. To temporarily retain the cover plate 19 in position on the cylinder 18 during assembling a resilient retainer 20 may be used. To secure the above parts in their operative position 15 a cover 21 is secured to the compressor wall 13 by means of screws one of which is shown at 22. A screw 23 of large size is threaded through this cover 21 and engages the lower end of the cover plate 19 for the 20 cylinder 18.

Adapted to operate within the cylinder 18 is a piston 24 which may be very loosely fitted so that it will slide freely. Within the piston 24 is the cylindrical end portion of a 25 second piston member 25 to which fingers 26 are attached at its upper end. In the lower position of the piston member 25 the fingers 26 are not in contact with the valve plate 12. Movement upward of this piston member 25 30 and the fingers 26 by the piston 24 forces the fingers 26 against the valve plate 12 to raise and hold the valve plate 12 in its open position.

In order to raise the piston 24 and the piston 35 member 25, fluid may be admitted into the lower end of the cylinder 18 through port extending centrally through the cylinder cover plate 19 and the retaining screw 23. With the piston 24 in its upper position the 40 upper bevelled end 27 of the piston 24 is adapted to contact with a tapered seat 28 on the cylinder 18. These coacting surfaces 27 and 28 are carefully ground or otherwise finished so that when in contact they are in fluid 45 tight relation and fluid is prevented from leaking past the cylinder 18 and into the intake passages 14. In this position of the piston 24 the fingers 26 are held upward in contact with the valve plate 12 under the full 50 pressure of the compressed fluid supplied through the screw 23 as from a pilot valve (not shown) associated with the compressor receiver. Upon releasing or exhausting fluid from within the cylinder 18 the piston member 55 25 is forced downward by means of a coiled spring 29 interposed between the valve seat 10 and piston member 25.

When the piston member 25 is in its lower position, which position it assumes during the 60 normal operation of the compressor, it is desirable that fluid be prevented from escaping from the intake passages 14 past the cylinder 18 and through the conduit through the screw 23. For this purpose the upper end 65 surface 30 of the cylinder 18 is carefully

ground or otherwise finished so that it may be in pressure tight contact with an annular surface 31 on the piston member 25. When the passages 14 are at a pressure above atmospheric as when the cylinder 18 forms an intermediate or high pressure cylinder of a compound compressor fluid will be prevented from escaping during the normal operation of the compressor.

I claim:

1. In a compressor valve lifting device, a cylinder having at one end integral seats disposed oppositely to one another, a detachable head closing the outer end of said cylinder, an actuating piston comprising two relatively 75 movable piston members movable within said cylinder and formed by two telescoping members, a surface on each member adapted to contact in fluid tight relation consecutively with its own seat on said cylinder when the 80 piston passes from one end of its movement to the other within the cylinder.

2. In a compressor valve lifting device, a cylinder having seats formed thereon, and an actuating piston movable within said cylinder, said piston comprising two parts, each part having a surface adapted to contact in pressure tight relation consecutively with its own seat on said cylinder when the piston passes from one end of its movement to the 90 other within the cylinder.

3. In a compressor valve lifting device, a cylinder having seats formed thereon, an actuating piston movable within said cylinder, said piston comprising two parts, each part 100 having a surface adapted to contact in pressure tight relation consecutively with its own seat on said cylinder when the piston passes from one end of its movement to the other within the cylinder, and fluid pressure means 105 to move both parts of said actuating piston simultaneously in the same direction within said cylinder.

4. In a compressor valve lifting device, a cylinder having opposed seats formed thereon adjacent one end and an actuating piston movable within said cylinder, said piston comprising two parts, each part having a surface adapted to contact in pressure tight 110 relation consecutively with its own seat on said cylinder when the piston passes from one end of its movement to the other within the cylinder, fluid pressure means to move said piston so that one part engages its seat, and other means to move said piston in the 115 opposite direction to engage the other part with its opposed seat.

5. In a compressor valve lifting device, a cylinder having opposed integral seats oppositely disposed thereon, an actuating piston for said device movable within said cylinder and comprising two piston members one 120 within the other, and a surface on each piston member adapted to contact in fluid tight 125 relation consecutively with its own seat on 130

said cylinder when the piston passes from one end of its movement to the other within the cylinder.

6. In a compressor valve lifting device, a cylinder having opposed integral seats oppositely disposed thereon, an actuating piston for said device movable within said cylinder and comprising two piston members one within the other and slideable relative to each other, a surface on each piston member adapted to contact in fluid tight relation consecutively with its own seat on said cylinder when the piston passes from one end of its movement to the other within the cylinder, and fluid pressure means to simultaneously move said piston members in the same direction to engage a surface on one piston member with its seat.

7. In a compressor valve lifting device, a cylinder having at one end integral seats disposed oppositely to one another, a detachable head closing the outer end of said cylinder, an actuating piston comprising two relatively movable members movable within said cylinder and having surfaces thereon adapted to contact in fluid tight relation respectively with the seats on said cylinder when the piston is at one or the other end of said cylinder, one of said piston members having extensions thereon adapted to contact with and lift a valve, and fluid pressure means to effect movement of said actuating piston in the direction to effect lifting of a valve.

In testimony whereof, I hereto affix my
35 signature.

WILLIAM C. MERWARTH.
